UNITED STATES PATENT OFFICE.

LZ ADAM BROWN, OF ALTO, MICHIGAN, ASSIGNOR TO CORDUROY TIRE COMPANY, OF GRAND RAPIDS, MICHIGAN, A CORPORATION OF DELAWARE.

DESIGN FOR A PNEUMATIC RUBBER TIRE.

Application filed June 19, 1924. Serial No. 9,905. Term of patent 14 years.

To all whom it may concern:

Be it known that I, LZ ADAM BROWN, a citizen of the United States, residing at Alto, in the county of Kent and State of Michigan, have invented a new, original, and ornamental Design for Pneumatic Rubber Tires, of which the following is a specification, reference being had to the accompanying drawings, forming a part thereof, in which—

Figure 1 is a perspective view of pneumatic rubber tire showing my design;

Figure 2 is a view of the same looking toward the rotative axis thereof; and

Figure 3 is a radial cross sectional view of the same taken on line 3—3 of Figure 2.

I claim:

The ornamental design for a pneumatic rubber tire substantially as shown.

LZ ADAM BROWN.
